Primary Examiner — Cynthia M. Chin*(74) Attorney, Agent, or Firm* — Wayne Harper; Cynthia Flanigan(57) **CLAIM**

The ornamental design for a kids toy vehicle, as shown and described.

DESCRIPTION

FIG. 1 is a Perspective view of a kids toy vehicle in an alternate configuration with the seat raised, showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof;

FIG. 8 is other perspective view thereof;

FIG. 9 is another perspective Bottom view thereof, in an alternate configuration with the seat raised; and,

FIG. 10 is further perspective view Bottom view thereof.

The broken lines shown are included for the purpose of illustrating portions of the article which form no part of the claimed design.

1 Claim, 10 Drawing Sheets(56)
